UNITED STATES PATENT OFFICE.

CHARLES H. NORTON, OF WORCESTER, MASSACHUSETTS, ASSIGNOR TO NORTON
GRINDING COMPANY, OF WORCESTER, MASSACHUSETTS, A CORPORATION OF
MASSACHUSETTS.

OILING DEVICE FOR GRINDING-MACHINES.

1,191,986.

Specification of Letters Patent. Patented July 25, 1916.

Application filed April 28, 1915. Serial No. 24,562.

To all whom it may concern:

Be it known that I, CHARLES H. NORTON, a citizen of the United States, residing at Worcester, in the county of Worcester and 5 State of Massachusetts, have invented a new and useful Oiling Device for Grinding-Machines, of which the following is a specification.

This invention relates to a grinding machine and more particularly to devices for supplying oil to the bearings of the grinding wheel shaft.

In commercial grinding machines, as at present designed, the grinding wheels are 15 rotated at a very high speed and the conditions of service are very severe. Accordingly the problem of an adequate oil supply has become very important.

It is the object of my present invention 20 to improve the construction of oiling devices in mechanism of the class described, attaining thereby increased simplicity in manufacture and greater efficiency in operation. With this object in view I have provided an oiling mechanism which is mounted upon the wheel shaft slide and is driven directly from the wheel shaft itself.

My invention further consists in certain 25 devices, arrangements and combinations of parts which will be hereinafter described and more particularly pointed out in the appended claims.

A preferred form of my invention is shown in the drawings, in which—

30 Figure 1 is a side elevation, partly in section, of my improved oiling mechanism, and Fig. 2 is a vertical sectional view taken along the line 2—2 in Fig. 1.

Referring to the drawings, the wheel slide 35 is indicated at 10, and is longitudinally movable in inverted guides 11 forming a portion of the wheel slide support. The wheel shaft 12 is mounted in shaft bearings 13 and 14 which are supported in arms or brackets 15 and 16 extending downwardly from the wheel slide 10 and forming portions thereof.

A depending casing 17 is secured to the lower end of the arm 16 and is provided with pockets 18 and 19 within which the oil 40 returned from the bearings is collected. The pocket 18 is connected by a pipe 20 to the oil space which underlies the bearing 13, while the pocket 19 is directly connected with the oil space of the bearing 14.

The specific construction of the bearings 55 13 and 14 forms no part of my present invention, but it may be stated that the bearings shown each consist of two bearing elements separated by spaces 21 and 22, which may be filled with felt or other material 60 which will permit free circulation of oil therethrough.

Within the casing 17 there is secured a sleeve 23 having a straight portion which constitutes a bearing for a short shaft 24 65 and having an enlarged portion at one end which constitutes a chamber 25 for the rotary pump or fan member 26. The shaft 24 carries a spur gear 27 which meshes with a similar spur gear 28 mounted upon the 70 wheel shaft 12. The pump chamber 25 is connected by a substantially vertical pipe 29 to a distributing pipe 30 having a branch 31 extending to the upper portion of the bearing 13 and a branch 32 extending to a 75 thrust bearing 33, at one end of the wheel shaft and adjacent the bearing 14.

The oil passing through the branch 31 may reach the bearing 13 through the oil 80 recess 22 (Fig. 2) while the oil passing through the branch 32 will pass downward through the inlet 34 to an oil recess 35 and thence through radial grooves 36 to an oil 85 space which communicates with the oil openings 21 and 22 of the bearing 14.

For a full description of the construction 90 of the bearings 13 and 14 and the thrust bearing 33 reference is made to my companion applications, Serial No. 24561 and Ser. No. 24563, filed on even date herewith.

With the construction above described, the oil circulating mechanism is necessarily 95 in operation whenever the wheel shaft is in rotation, the speed of the oil pump is controlled by the speed of the grinding wheel and shaft, and a positive circulation of the oil is assured at all times when the grinding wheel is in operation. By the location of the oil chamber below the wheel shaft and bearings I am enabled to utilize a gravity 100 flow from the bearings to the oil pump, while the flow of the oil from the pump to the bearings is positive and direct.

Having thus described my invention it will be evident that changes and modifications can be made therein by those skilled in the art without departing from the spirit and scope thereof as set forth in the claims 105

and I do not wish to be otherwise limited to the details herein disclosed, but

What I do claim is:—

1. In a grinding machine, in combination, a movable wheel slide, a wheel shaft supported in bearings on said slide, means to rotate said shaft, and self-contained means to produce a forced circulation of oil through said bearings, said oil-circulating means being entirely supported by said slide and movable therewith, and being positively and directly driven from the wheel shaft.

2. In a grinding machine, in combination, a movable wheel slide, a wheel shaft supported in bearings on said slide, means to rotate said shaft, and oil-supplying means for said bearings, said latter means comprising an oil pump carried by said slide and movable therewith, a positive driving connection

from said wheel shaft to said pump, and oil-conveying connections between said pump and the shaft bearings.

3. In a grinding machine, in combination, a movable wheel slide, a wheel shaft supported in bearings on said slide, means to rotate said shaft and oil supplying means for said bearings, said means comprising an oil collecting chamber carried by said slide below the level of said bearings, oil conducting connections from said bearings to said chamber, a rotary oil pump in said chamber, direct gear connections from the wheel shaft to said oil pump for driving said pump, and oil distributing connections from said oil pump to said bearings. 35

In testimony whereof I have hereunto set my hand.

CHARLES H. NORTON.
